EXERCISING DEVICE

Maurice E. Painter, Brookville, Ohio

Application October 10, 1938, Serial No. 234,115

9 Claims. (Cl. 272—79)

This invention relates to an exercising device and one object of the invention is to provide such a device the operation of which will involve the use of a large part of the muscles of the body and will be easy and agreeable.

A further object of the invention is to provide an exercising device comprising a seat supported by a resilient bar which is of such a character and so mounted that it will have little or no tendency to crystallize and break, and having means operable by the occupant of the seat for flexing said resilient bar.

A further object of the invention is to provide such an exercising device which will be simple in its construction and operation and of a strong durable character.

Other objects of the invention may appear as the apparatus is described in detail.

In the accompanying drawing Fig. 1 is a plan view of an exercising device embodying my invention; Fig. 2 is a side elevation of such an exercising device; Fig. 3 is a rear elevation of the same partially broken away; Fig. 4 is a detail of a head gear for use in actuating the exercising device; and Fig. 5 is a transverse section taken on the line 5—5 of Fig. 2.

In the drawing I have illustrated one embodiment of my invention and have shown the same as comprising a base which preferably consists of a bar 10 supported at its ends by front and rear transverse supporting members 11 and 12. Mounted on the forward portion of this base and extending upwardly and rearwardly therefrom is a resilient bar 13 having mounted thereon near the free end thereof a seat 14 and also having mounted thereon, in front of the seat, foot rests which are here shown as the end portions of a transverse bar 15. Preferably both the seat and the foot rests are adjustable lengthwise of the bar and for that purpose the seat 14 is carried by a sleeve 16 slidably mounted on the bar and secured in adjusted position thereon by a thumb screw 17. The foot rests are likewise carried by a sleeve 18 slidably mounted on the bar and secured in adjusted positions thereon by a thumb screw 19.

The resilient bar is of such a character and is so mounted on the base that it will flex about a variable axis, or a plurality of axes, and will have little tendency to crystallize and break. In the preferred form the forward portion of the bar 13 is curved downwardly and forwardly to provide the same with a forwardly curved portion 20 which terminates in a relatively short rearwardly extending portion 21 which is secured to

the forward portion of the base. To minimize the tendency of the resilient bar to crystallize and break it is desirable that the lower portion 21 thereof shall be tiltable about a transverse axis. To permit of such tilting action the base bar 10 is formed of resilient material and the front transverse member 11 of the base is adapted to tilt about an axis transverse to the base bar and to the resilient bar 13. Preferably this front transverse member 11 has its floor engaging portions 22 rounded or otherwise shaped to permit the same to have a rocking motion on the floor. The lower portion 21 of the resilient bar 13 extends across the front transverse member 11 of the base and is rigidly secured to that member and is also secured to the resilient base bar 10 at a point a short distance in the rear of the transverse member 11. As a result of this arrangement the flexing action of the upper portion of the resilient bar 13 will move the lower portion 21 thereof about a transverse axis, thus tilting the transverse member 11 and flexing the base bar 10, which yieldably resists the movement of the parts 21 and 11. Preferably the rear transverse member of the base is held against movement on the floor and this may be conveniently accomplished by providing the same with a frictional floor engaging surface 23, such as rubber or leather. When the device is designed for the use of adults the resilient bar 13 is necessarily of heavy and relatively stiff material and inasmuch as the resilient base bar must resist and limit the tilting movement of the lower portion 21 of the bar 13, and of the transverse supporting member 11, the base bar should be relatively stiff so that it will offer the desired resistance to the movement of the other parts. Preferably this base bar is in the form of a downwardly facing channel, as shown in Fig. 5, and, if desired, the flanges of the channel may be connected by transverse members 24, welded or otherwise secured thereto, to prevent the spreading of the flanges when the base bar is flexed.

Suitable means are provided whereby the person occupying the seat 14 may actuate the device by first flexing the seat supporting bar 13 and then releasing the same. In the present embodiment of the invention two means have been provided which may be separately used for flexing the seat supporting bar. One of these actuating means comprises a flexible pull member, here shown in the form of a flat strap 25, which may be made of any suitable material which has the necessary strength and flexibility, such as fabric or leather. This strap is connected at one end

with the seat supporting bar 13 adjacent to the seat 14, by means of an attaching device 26. It extends downwardly from the seat and through an opening 27 in the horizontal portion of the base bar 10 where it passes about a guide pulley 28 supported on the base bar and extends forwardly through the channel to a point beyond the base where it passes about a pulley 29 and thence upwardly and about a pulley 30. The pulleys 29 and 30 may be supported in any suitable manner but are here shown as carried by brackets 31 and 32 mounted directly upon the curved portion 20 of the resilient bar and so arranged that the pulley 29 will be supported at a point in line with the base bar and in front of the curved portion of the bar 13, and the pulley 32 will be supported above and in front of the curved portion 20 of the bar. The strap extends from the pulley 30 upwardly and rearwardly above the upper portion 13 of the resilient bar, and is provided at its upper end with hand grips 33, which are here shown as formed on the ends of a transverse handle bar secured to the strap. The strap is of such length that the hand grips will normally be located adjacent to the foot rests and in order to grasp the same a person on the seat 14 must bend far forward. When he has grasped the hand grips he straightens up and exerts a pull on the pull strap thereby moving the seat downwardly against the action of the resilient bar, the amount of movement thus imparted to the seat depending upon the strength of the pull exerted on the strap. When the seat has been depressed as far as the occupant desires, or is able, to depress it the pull on the strap is relieved and the seat permitted to return to or above its elevated position by the inherent resiliency of the bar 13. This return movement will usually carry the seat upwardly beyond its normal position, that is, the position to which it would be moved solely by the weight of the occupant. As the seat reaches the upper limit of its movement and starts downwardly a second pull is exerted on the pull strap, and by repeating this operation a vertical swinging movement may be imparted to the seat. In order to initiate and maintain this swinging movement repeated pulls must be exerted on the strap and inasmuch as the upward movements of the seat and its supporting bar will cause the hand grip to return to its normal position adjacent the foot rests it will be apparent that the operation of the device involves the use of many muscles of the torso as well as the arm and leg muscles, and the swinging movement of the seat renders the exercise pleasant and agreeable.

The pull strap may be actuated by means other than the hand grips and in Fig. 4 I have shown a head gear adapted to be connected with the pull strap 25 whereby the strap may be actuated wholly by the neck and body muscles without the use of the arms. As here shown, this head gear comprises a strap loop 34 adapted to extend about the head of the seat occupant and having means for connecting it with the pull strap, such as a snap hook 35 adapted to engage a ring 36 on the pull strap. The strap loop 34 is preferably provided with upwardly extending straps 37 and 38 arranged to fit over the head and support the strap 34 in proper position on the head. When this head gear is used the occupant of the seat releases the hand grips 33 and uses his body and neck muscles to flex the seat sup-

porting bar, the legs of course being braced against the foot rests.

The hand grip 33 may be adjustably connected with the pull strap 25 to enable the same to be adjusted in accordance with the needs of different occupants of the seat, and for this purpose the strap may be connected with the transverse bar of the hand grips by a buckle 33a or the like, any excess length of the strap being carried about the bar 33 and then forwardly beneath the same. Likewise this pull strap may be connected with the resilient bar 13 at different distances from the end thereof to modify its action on that bar, and in Fig. 2 I have shown the bar as provided with a second device, 26a, 15 by means of which the strap may be connected therewith.

In order to further vary the manner of operating the device a second flexible pull member 39 is provided. As here shown the pull member 39 is in the form of a cord or light cable, the intermediate portion of which is supported by a pulley 40 connected with the resilient bar 13 adjacent the seat 14. The two parts of this cable 39, on opposite sides of the pulley, extend downwardly and laterally and pass respectively about pulleys 41 secured to the rear transverse member 12 of the base on opposite sides of the base bar 10. From the pulleys 41 the two parts of the cable 39 extend forwardly and pass about pulleys 42 connected with the front transverse member 11 of the base. The end portions of the cable, beyond the pulleys 42, are free to extend upwardly, as shown in Fig. 2, and each part is provided at its upper end with a hand grip 43. 35 The pull cable 39 is of such a length that the hand grips may extend a substantial distance beyond the foot rests so that they may be grasped by the occupant of the seat while he is in a substantially upright position on the seat and the two parts of the cable actuated by the arms alone, the arrangement being such that the arms may move above the shoulders and outwardly to a straight position. The cable being supported by the pulley 40 it will be obvious that the two 45 parts thereof may have longitudinal movement in opposite directions and that the arms of the seat occupant may move in various directions.

When the cable 39 and hand grips 43 are used to flex the resilient seat supporting member the pull strap 25 is idle and, if desired, it may be supported in an idle position above the bar by engaging the ring 36 with a hook 44 carried by the sleeve 18 which supports the foot rests. When the pull strap 25 is used in operating the device the hand grips 43 and the end portions of the pull cable 39 may lie on the floor alongside the apparatus, or in any other suitable position in which they will not interfere with the operation of the apparatus by the pull straps 25. 60

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. In an exercising device, a base, a resilient bar mounted on the forward portion of said base and extending upwardly and rearwardly therefrom, a seat secured to said bar near the free end thereof, a foot rest secured to said bar in front of said seat, guides near the respective ends of said base, a flexible member connected with

5 said resilient bar adjacent to said seat, extending downwardly therefrom and about said guides, and then upwardly and rearwardly, and actuating means connected with the upper end of said flexible member to enable a person on said seat to exert a pull on said flexible member.

2. In an exercising device, an elongate base, a resilient bar having its forward portion bent downwardly and rearwardly and having a lower portion secured to the forward end of said base and an upper portion extending upwardly and rearwardly to a point above the rear portion of said base, a seat secured to said upper portion of said bar near the rear end thereof, a foot rest 10 secured to said upper portion of said bar in front of said seat, guide pulleys carried by said device adjacent to the respective ends of said base, a flexible pull member connected with the upper portion of said bar adjacent said seat, extending downwardly therefrom and about the pulleys at both ends of said base, and hand grips connected with said flexible member beyond the pulley at the forward end of said base, said flexible member being of such length that said hand grips 15 may be grasped by a person occupying said seat and a pull exerted on said flexible member to move the rear end of the upper portion of said bar downwardly.

3. In an exercising device, a base comprising a resilient bar and transverse floor engaging members secured to the respective ends of said bar, the transverse member at the front end of said bar being tiltable about an axis transverse to said bar to permit said bar to flex, a second resilient bar having its forward portion curved downwardly and rearwardly to provide the same with a short lower portion and a relatively long upper portion, said lower portion extending across and being secured to the front transverse member of said base and being secured to the resilient bar of said base at a point spaced a short distance to the rear of said front transverse member, guide pulleys supported respectively adjacent the front and rear ends of said base, a flexible pull member connected with the upper portion of said second resilient bar near the rear end thereof and extending about said pulleys, hand grips connected with said pull member beyond the front pulley, and a seat carried by the upper portion of said second resilient member near the rear end thereof.

4. In an exercising device, a base comprising a resilient bar and transverse floor engaging members having supporting connection with the respective ends of said bar, a second resilient member having a relatively short lower portion, a longer upper portion and a forwardly curved portion connecting said lower and upper portions, said lower portion extending across and being secured to the front transverse member of said base and being secured to the resilient base bar in the rear of said front transverse member, a seat carried by the upper portion of said second bar, a foot rest carried by said upper portion in front of said seat, pulleys supported adjacent the respective ends of said base, a flexible pull member connected with the upper portion of said second bar adjacent to said seat and extending about said pulleys, and hand grips connected with said pull member and adapted to be grasped by a person on said seat, whereby a pull on said pull member will flex said second bar, the front transverse member of said base having its floor engaging parts shaped to permit said member to tilt about an axis transverse to said base and

thereby enable said resilient base bar to be flexed by the action of said second bar, and the rear transverse member of said base having a frictional floor engaging surface to prevent the movement of said rear member by the flexing of said base bar.

5. In an exercising device, a base, a resilient bar supported on the forward portion of said base and extending upwardly and rearwardly therefrom, a seat on said bar, a foot rest on said bar in front of said seat, guide members at the front and rear ends of said base, a flexible pull member connected with the rear portion of said bar, extending downwardly therefrom and about the rear guide member, then forwardly and about the front guide member, thence upwardly and rearwardly above said bar, and an actuating device connected with said pull member whereby a person on said seat may exert a pull on said pull member to flex said bar.

6. In an exercising device, a base comprising an elongate member and supporting members connected with the respective ends of said elongate member, a resilient bar having its forward portion curved downwardly and rearwardly and secured to the forward portion of said base, a seat carried by the rear portion of said bar, a foot rest carried by said bar in front of said seat, said elongate member having an opening in the rear portion thereof, a pulley supported adjacent to said opening, other pulleys supported adjacent to and in front of the curved portion of said bar, a pull member connected with the rear portion of said bar, extending through the opening in said base member and about the first mentioned pulley, then forwardly beneath the elongate member of said base and about the last mentioned pulleys and then rearwardly above said bar and a hand grip connected with said pull member.

7. In an exercising device, a base comprising an elongate member and supporting members connected with the respective ends of said elongate member, a resilient bar having its forward portion curved downwardly and rearwardly and secured to the forward portion of said base, a seat carried by the rear portion of said bar, a foot rest carried by said bar in front of said seat, said elongate member having an opening in the rear portion thereof, a pulley supported adjacent to said opening, other pulleys supported adjacent to and in front of the curved portion of said bar, a pull member connected with the rear portion of said bar, extending through the opening in said base member and about the first mentioned pulley, then forwardly beneath the elongate member of said base and about the last mentioned pulleys and then rearwardly above said bar, and means for connecting said pulley member with the head of a person on said seat.

8. In an exercising device, a base, a resilient bar supported on the forward portion of said base and extending upwardly and rearwardly therefrom, a seat on said bar, a foot rest on said bar in front of said seat, a pulley connected with the rear portion of said bar, a pair of guide members on the rear portion of said base, a second pair of guide members on the front portion of said base, a pull member having its intermediate portion supported on said pulley, the two parts of said pull member extending downwardly from said pulley and about the respective rear guide members and then forwardly about the respective front guide members, and hand grips connected with the ends of said pull member.

9. In an exercising device, a base, a resilient

bar supported on the forward portion of said base and extending upwardly and rearwardly therefrom, a seat on said bar, a foot rest on said bar in front of said seat, guide members at the front and rear ends of said base, a flexible pull member connected with the rear portion of said bar, extending downwardly therefrom and about the rear guide member, then forwardly and about the front guide member, thence upwardly and rearwardly above said bar, an actuating device connected with said pull member whereby a person on said seat may exert a pull on said pull member to flex said bar, a pulley connected with the rear portion of said resilient bar, a pair of

guide members on the rear portion of said base, a second pair of guide members on the front portion of said base, a second flexible pull member having its intermediate portion supported on said pulley, the two parts of said second pull member extending downwardly from said pulley and about the respective rear guide members and then forwardly and about the respective front guide members, and hand grips connected with the ends of said pull member, the two pull members being so arranged that either pull member may be used to flex said bar without interference by the other pull member.

MAURICE E. PAINTER.
